FOURDRINIER BELT

Edward J. Buell, Niagara Falls, N. Y., assignor
to The Lindsay Wire Weaving Company,
Cleveland, Ohio, a corporation of Ohio

Application November 28, 1931
Serial No. 577,831

5 Claims. (Cl. 245—10)

This invention relates to a seam for woven wire belts, as well as to a method of making the same, and has particular application to wire belts which are used for paper-making machines.

- 5 Where such belts are made with a twill weave, considerable difficulty has been experienced in making a seam, that would maintain the end weft wires in position with reference to the warp wires, and yet have sufficient strength to withstand the repeated bending to which the seam is subjected during use. Many efforts have been made to solve this problem by reinforcing each end of the belt by a stitching wire, and then connecting the ends together with a lacing wire.
- 10 This necessitates excessive amount of wire in the region of the seam and tends to clog the seam opening, and thereby to mark the sheet of paper to an objectionable degree.

To minimize the amount of wire in the region 20 of the seam, the suggestion has been made of removing the last weft wires and replacing them with silver solder covered wires, and then applying heat so as to join the weft wires and the overlapping ends of the warp wires together.

25 This form of seam was objectionable however, for it made the seam too rigid and unyielding, and as a result, the belts cracked in the region of the seam before the fabric itself had worn out.

An object of my invention therefore, is to make 30 a seam, which has the advantage of a small amount of wire in the region of the joint, and also sufficient flexibility and mechanical strength to withstand the alternate bending and straightening to which the seam is subjected during use.

35 In this connection, my invention is concerned with a seam, which is also applicable for use with a belt having a plain weave.

Referring now to the drawing, Fig. 1 is a top plan view on an enlarged scale of part of a belt 40 having a seam made in accordance with my invention, and utilizing a plain weave; Fig. 2 is a similar view showing the use of the invention in connection with a belt having a twill weave; Fig. 3 is a section taken on the line 3—3 in Fig. 45 2; Fig. 4 is a section taken through part of a belt adjacent the seam and showing the picket ends opened while Fig. 5 is a similar section showing the ends in contiguous relationship and the pickets closed.

50 I have shown my invention in Fig. 1 as applied to a belt having a plain weave. In such view, the warp wires are indicated at 10 and the weft wires at 11, the last weft wires at the ends of the belt being indicated at 11a and 11b respectively. These end weft wires are the usual

wires, which are woven into the fabric during the weaving operation. The fabric is cut to the proper length, and the warp pickets are cut off short to the end weft wire. If desired, the warp pickets may be allowed to overhang the weft 60 wires and then opened as shown in Fig. 4 to admit the opposite weft wire. The two weft wires 11a and 11b are then brought into contiguous relationship, the pickets are closed as shown in Fig. 5 and while so held are brazed together by the 65 application of heat. If desired, solder may also be applied simultaneously with the heat.

After the brazing operation is completed, I prefer to reinforce the joint by the application 70 of a lacing wire 15, which may be passed across the seam in any desired manner. That illustrated in Fig. 1 has the lacing wire passing over the second last weft wire, and through alternate openings across the width of the belt. By brazing the two weft wires, as hereinbefore described, 75 I can utilize a small lacing wire, which lies below the planes of the top and bottom surfaces respectively of the belt. Thus, the lacing wire is protected and yet the seam is sufficiently strengthened to withstand the tension and bending strains to which it is subjected during use. 80 I have found for example, that satisfactory results can be accomplished by utilizing a lacing wire having a diameter of .007 inches with warp and weft wires having a diameter of .010 inches. 85 I do not wish to be limited to these sizes however, for I am merely illustrating them to enable anyone skilled in the art to make the belt.

In Fig. 2, I have shown a twill weave, wherein the warp and weft wires are indicated at 20 and 90 21 respectively, and wherein the end weft wires are referred to at 21a and 21b respectively. Such last-named wires are joined together in the same manner as that described for the plain weave, and then a lacing wire 22 is used for reinforcing 95 the seam. The lacing wire, which I employ is smaller in diameter than the other wires and is passed through the belt on opposite sides of the seam, and in such positions that will avoid the necessity for passing the lacing wire across the 100 top of any knuckle.

I have found that a satisfactory arrangement for this type of weave is to pass the lacing wire alternately over the last and second last weft wires at each end of the belt. Obviously, the 105 wire 22 could be laced in a different manner, but that illustrated provides sufficient strength while allowing ample opening for drainage purposes.

The principal advantages of a seam made in accordance with my invention is the fact that the 110

brazing or uniting of the two end weft wires minimizes the amount of wire that must be used in the region of the seam, while the lacing or reinforcing wire provides sufficient strength to withstand the repeated alternate bending and straightening to which the belt is subjected during use. Furthermore, the seam enables one to use a relatively small lacing wire, wherefore it is protected against undue wear, and the full advantage resulting from the use of twill weave can be obtained.

I claim:

1. A method of making a seam for a woven wire belt having warp wires and weft wires, comprising bringing the end weft wires in their entirety together in contiguous relationship, brazing them together by the application of heat, and then reinforcing the joint with a lacing wire.
2. A method of making a seam for a woven wire belt, comprising opening the picket ends, moving the ends together until the last weft wire on each end of the belt is disposed between the pickets at the other end and in contiguous relation therewith, and applying sufficient heat to weld the

weft wires together and also to weld the picket ends of the warp wires to the respective weft wires.

3. A seam for a woven wire belt, having the two end weft wires brazed together in their entirety solely by the application of heat, and a reinforcing lacing wire extending across the joint.

4. A method of making a seam for a woven wire belt having warp wires and weft wires, comprising bringing the end weft wires in their entirety at each end of the belt into contiguous relationship, applying a fusible material, heating the wires and the fusible material to effect an autogenous connection, and then reinforcing the joint with a lacing wire.

5. A seam for a woven wire belt, having the last weft wires adjacent the seam soldered together in their entirety in contiguous relationship, and having a lacing wire passing around the weft wires and reinforcing the joint, said lacing wire being smaller than the warp wires.
